UNITED STATES PATENT OFFICE.

THOMAS NATHAN RUSSELL, OF CHICAGO, ILLINOIS, ASSIGNOR TO CHICAGO-CLEVELAND
CAR ROOFING COMPANY, A CORPORATION OF ILLINOIS.

CAR-ROOF.

1,080,173.

Specification of Letters Patent.

Patented Dec. 2, 1913.

Application filed July 10, 1912. Serial No. 708,581.

To all whom it may concern:

Be it known that I, THOMAS NATHAN RUSSELL, a citizen of the United States, residing in Chicago, in the county of Cook and 5 State of Illinois, have invented a new and useful Improvement in Car-Roofs, of which the following is a specification.

The invention relates to outside metal roofs for freight cars, and has for its principal object to so unite the roof sheets and their connecting and securing parts that the roof will be water-tight and also flexible in 10 its seams. Such flexibility prevents the roof from being damaged by the torsional strain's and movements to which the frame work of 15 the tops of freight cars are subject in service. This result is largely obtained by leaving each roof sheet or section sufficiently free 20 and independent of other roof sheets or sections so that it will absorb all of the strain to which it may be subjected, without communicating such strain in any injurious degree to other parts of the metal covering. The several roof sheets have a free lateral 25 and longitudinal movement relative to each other when the said torsional or lateral strains occur in the framework of the car, without straining or damaging the sheets or their connecting and securing means, and 30 without impairing the water-tight character of the roof.

With such objects in view the invention consists in the parts and combinations thereof hereinafter set forth and claimed.

35 In order to make the invention more clearly understood there are shown in the accompanying drawings means for carrying the same into practical effect, without limiting the improvements, in their useful application, to the particular construction which, for the purpose of example, has been delineated.

40 In said drawings:—Figure 1 is a plan view, partly broken away, of a portion of a freight car roof embodying the invention. Fig. 2 is a side view of the same. Fig. 3 is a transverse vertical section of the same on line III—III of Fig. 1, the view being on a larger scale and partly broken away. Fig. 4

is a similar view, on a still larger scale, on 50 line IV—IV of Fig. 1. Fig. 5 is a vertical, longitudinal, sectional view of a portion of one end of the roof, on line V—V of Fig. 1. Fig. 6 is a vertical longitudinal section across two roof sheets and their seam cap, 55 the sheets being partly broken away. Fig. 7 is a perspective view of a roof sheet. Fig. 8 is a perspective view of a seam cap, showing the end portions of the same, the intermediate portion being broken away. Fig. 9 60 is a perspective view of a ridge cap.

Referring to the drawings, 1 is the ridge pole of a freight car, 2 the side plates, 3 the carlines, 4 the top sheathing, which may run longitudinally, as shown, or transversely of 65 the car; 5 the side sheathing, 6 the fascia, 7 the walk sleepers and 8 the walk. 9 indicates the end plates, and 10 the end sheathing (Fig. 5). These parts may be of any usual or preferred and suitable construction. 70

11 indicates the roof plates, of suitable sheet metal, which are laid side by side on the top sheathing, extending from the fascia to the ridge pole, at both sides of the roof. The roof plates are bent at their edges to 75 form flanges whereby they are connected with the car body, and are connected loosely, flexibly or movably with each other. 12 is a down turned flange at the lower or outer edge of the sheet which fits over the side 80 fascia 6 of the car.

13 is an upturned flange at the upper or inner end of the sheet.

14, 14 are upwardly and inwardly turned flanges at the sides of the sheet, terminating 85 in downwardly extending edges 15, 15 so arranged as to leave between the parts 14 and 15 a space 16. At the corners of the inner end of the sheet the flanges 14 are united with the flange 13, the superfluous 90 metal being bent and folded as indicated at 17, the corners of the sheet having first been notched. This connection closes the corners and keeps the inner end of the flange 14 at the desired inward inclination. The 95 edges 15 pass down at the side of the flange 13, as seen in Fig. 7.

The inverted and inclined U-shaped flange,

which is thus formed by the parts 14 and 15, is connected with the similar flange of the adjacent sheet by a seam cap (Fig. 8) which is composed of a section of sheet metal 5 formed in the shape of approximately three-fourths of a hollow cylinder 18, with two flanges 19, 19 extending inward and turned outward toward the wall of the cylinder at an angle to the vertical, thus leaving side 10 spaces 20, 20 and a middle space 21. At its inner end next to the ridge pole the seam cap is formed with a flange 22 which may be bent down to close or partly close the end of the cap and abut against the ends of the 15 roof plate flanges 14, 15 (Figs. 4 and 8). The seam cap is assembled with the roof sheets 11, as best seen in Fig. 6, by properly interlocking it with the adjacent flanges 14, 15 of the roof sheets and then, sliding it 20 longitudinally of the seam into place. If the seam cap be so applied at the outer ends of the roof sheets, the flange 22 will be bent down after the seam cap is in place. After the parts are thus connected free movement 25 of the roof sheets can take place in the seam cap, independent of each other and of the cap. The flange edges 15 have the spaces 20 to move in, and the flanges 19 have the spaces 16 which permit the free relative 30 working of the parts 15, 19 and 14.

The seam cap 18, 19 is so designed that the sections on the under side, where the flanges turn inward, are so shaped at the bends 23 that should a slide of ice or snow 35 falling off a roof strike the seam, the seam will not open up and cause the roof to leak, but will cause the seam cap to close up into the corners of the flanges on the sheets at the bends 24, this making the seam tighter, 40 instead of its opening up, as occurs with other types of seams.

The seam caps at opposite sides of the ridge of the car roof are in line with each other, their ends nearly abutting as seen in 45 Fig. 4, space being left for the vertical securing bolt 25 which passes down between them.

26 indicates the ridge cap (Fig. 9), a series of which caps, lapping over and under one another alternately, extends for the entire length of the car at the ridge and loosely connects the roof plates at one side of the ridge with those at the other side. Each ridge cap is formed with a longitudinal 55 inverted U-bend 27 which incloses the inner upstanding flanges 13 of the contiguous roof plates, one at each side of the ridge. Between the ends of the bend 27 the cap is formed with a short transverse inverted U-bend 28 which intersects with the bend 27 and is of such diameter as to inclose the abutting ends of two seam caps (Figs. 1 and 3). At the intersection is formed a hole 29 for the bolt 25. At the sides of the bend 27

are formed flanges 30 which are slightly inclined downward to correspond with the slopes of the roof. The ends of the flanges 30 remote from the bend 28 are turned up to form vertical (or slightly inclined from the vertical) flanges 31 which fit within the 70 bend 28 of the next adjacent ridge cap and between the inner face of such ridge cap and the outer face of the seam cap (Fig. 2). The ridge caps are thus locked with each other against relative longitudinal displacement being also interlocked against relative lateral displacement by the lapping of the bends 27.

The walk sleepers 7 are or may be shaped on their under sides, as by grooves, to fit 80 over the ridge caps and seam caps and rest on the roof plates. The walk sleeper is formed with a recess 32 on its upper side to receive the head 33 of the bolt 25.

34 is a bolt head cover of sheet metal or 85 water proof material fitted over the bolt head and recess to exclude rain and prevent rotting of the sleeper. The walk 8 is secured on the sleepers 7 in the usual manner. The bolts 25 pass down through the sleeper, 90 the hole 29 in the ridge cap, between the seam caps, and through the top sheathing, ridge pole and carline, against the under side of which latter bears its washer and nut 35.

The outer edges of the roof sheets and their depending flanges 12 are clamped upon the top sheathing and against the fascia or crown molding by sheet clips 36 of malleable iron which are secured by a bolt 37, which 100 extends to the inner side of the side plate 2, and by a wire nail 38. These clips have upwardly and inwardly inclined arms 39 which bear down on the roof sheets.

The outer end of the seam cap is held 105 within a seam cap casting 40 of malleable iron, having a depending arm 41. This arm bears against the roof sheet flange 12, and below the latter is secured to the car by a bolt 42 extending through to the inner side 110 of the side plate, and by wire nails 43, 43 driven into the fascia. The inward part of the casting 40 supporting the seam cap has three ribs 44, one at the top and one at each lower side, connected by a ring or collar 45 at their inner ends and joined at their outer ends to the arm 41. The said two ribs 44 at the sides extend downward and inward and support the seam cap on the under side and hold it up to limit the contact of the 115 flanges 19, at their edges, with the top bend of the roof sheet flange, and of the edges of the roof sheet flanges 15 with the bottom bends of the seam cap, so as to prevent wear by chafing at these points. The lateral apertures in the hood-portion of the casting 40, formed by the ribs 44 and collar 45, also 120 lessen wear on the end of the seam-cap and

prevent the accumulation of moisture and cinders that would tend to rust out such seam-cap end.

All of the roof sheets, except the end 5 finishing sheets, are facsimiles of each other in size and form. The end sheets 46 are or may be narrower than the sheets 11 and are made rights and lefts, and they have only one upstanding flange 14, and at their outer 10 side are formed with depending flanges 47 which are secured to the outer face of the end fascia 48 (Fig. 5).

The outer ends of the ridge cap at the two ends of the roof are inclosed by ridge cap 15 clips 49, which are formed with inverted U-shaped portions 50 adapted to inclose the bends 27 of the ridge caps, with horizontal or slightly inclined flanges 51 which rest on the ridge cap flanges 30 and with depending 20 arms 52. The arm 52 is secured by bolts 53 which pass through the end fascia and end plate 9.

What is claimed is:—

1. In a freight car roof, the combination 25 of roof plates having at their sides upturned inverted U-shaped flanges having spaces allowing for relative lateral movement of the roof plates in directions transverse to the seam, and a seam cap inclosing the flanges 30 of the roof plates and having upturned flanges engaging within the said flanges of the roof plates, and having spaces between its flanges and between its flanges and the inclosing walls of the cap allowing relative 35 lateral movement of the roof plates in directions transverse to the seam, the seam cap being substantially cylindrical and having its lower portions inclined outward and upward away from the middle of the seam, 40 substantially as set forth.

2. In a freight car roof, the combination 45 of roof plates having at their sides upturned inverted U-shaped flanges inclined outwardly away from the line of the seam and having spaces allowing for relative lateral movement of the roof plates in directions transverse to the seam, and a seam cap inclosing the flanges of the roof plates and having upturned outwardly inclined flanges 50 engaging within the said flanges of the roof plates, and adapted to brace outwardly against the interior of the said U-shaped flanges and toward the sides of the cap, and having spaces between its flanges and between its flanges and the inclosing walls of 55 the cap allowing relative lateral movement of the roof plates in directions transverse to the seam, substantially as set forth.

3. In a freight car roof, the combination 60 of roof plates having at their sides upturned inverted U-shaped flanges, a seam cap of tubular form inclosing and interlocking with said flanges, and having its

lower parts extended inward toward each other, and a seam cap clip attached at the 65 eaves of the roof and inclosing and supporting the outer end of the seam cap and engaging beneath and supporting the said inwardly extended parts of the cap, substantially as set forth.

4. In a freight car roof, the combination 70 of roof plates having upturned flanges at their inner ends along the ridge of the roof, seam caps engaging the sides of the roof plates, and ridge caps having inverted U- 75 bends inclosing the ridge flanges of the roof plates, and having transverse U-bends inclosing the seam caps, and having upwardly extended flanges 31 interlocking with the said transverse U-bends of the ridge caps, 80 whereby the ridge caps are interlocked with each other against both lateral and longitudinal movement, substantially as specified.

5. In a freight car roof, the combination 85 of roof plates having upturned flanges at their inner ends along the ridge of the roof and ridge caps having longitudinal inverted U-bends inclosing the said flanges, transverse U-bends, and upturned transverse flanges at the ends of the ridge caps, the 90 several ridge caps overlapping and interlocking directly with each other against longitudinal movement by means of said U-bends and upturned transverse flanges, substantially as set forth.

6. In a freight car roof, the combination 95 of roof plates having upturned flanges at their inner ends along the ridge of the roof, ridge caps having inverted U-bends inclosing the said flanges, overlapping one another and interlocked with each other by said U-bends against lateral longitudinal movement, and having at both ends transverse parts by means of which the ridge caps interlock with each other at both ends 100 against displacement in the longitudinal direction of the ridge, and ridge cap clips attached at the ends of the roof and inclosing the ends of the roof plate flanges and of the ridge caps, substantially as set 110 forth.

7. In a freight car roof, the combination 115 of roof plates having lateral flanges connected in upstanding tubular seams, and seam-end eaves-clips having depending arms secured to the side structure of the car and laterally apertured hood-portions embracing the seam-ends and engaging beneath the seams, substantially as set forth.

8. In a freight car roof, a ridge inclosure 120 or cap formed of similarly shaped sections, each section having at one end a transverse bend and having at the other end a transverse flange, the sections interlocking directly with each other at both ends by means 125 of said transverse bends and flanges, against

displacement in the longitudinal direction of the ridge, substantially as specified.

9. In a metal freight car roof, the combination, with the roof plates having side flanges, of tubular seam caps extending outward at their sides and inclosing the said side flanges, and eaves clips engaging be-

neath and supporting the eaves ends of the said seam caps, substantially as specified.
